UNITED STATES PATENT OFFICE.

SAMUEL S. CENTOFANT, OF SMITHS BASIN, NEW YORK.

VESSEL EMERGENCY-BRAKE.

1,078,902.

Specification of Letters Patent. Patented Nov. 18, 1913.

Application filed September 13, 1912. Serial No. 720,236.

To all whom it may concern:

Be it known that I, SAMUEL S. CENTOFANT, a citizen of the United States, residing at Smiths Basin, in the county of Washington, State of New York, have invented certain new and useful Improvements in Vessel Emergency-Brakes; and I do hereby declare the following to be a full, clear, and exact description of the invention, such as will enable others skilled in the art to which it appertains to make and use the same.

This invention relates to brakes and more particularly to ship brakes.

An object of the invention is to provide means for braking the speed of a vessel and which may be thrown into operation while the vessel is traveling at high speed.

Another object is to provide mechanism of this character which will be highly efficient and effective in use and which will be of extremely simple construction and operation.

Another object is to provide brake mechanism of this character including horizontally swinging leaves upon opposite sides of the vessel with means for controlling the swinging movement thereof embracing the same when in operative position.

Another object is to generally improve and simplify the construction of brakes of this character and increase the efficiency thereof.

With these and other objects in view my invention will be more fully described and illustrated in the accompanying drawings attached to and forming a part of this application, in which—

Figure 1 is a plan view, showing a portion of a hull of a boat to which my improved device is applied. Fig. 2 is a similar view with the brake mechanism in operative position. Fig. 3 is a side elevation, showing the brake mechanism in inoperative position. Fig. 4 is a vertical sectional view on the line 4—4 Fig. 1. Fig. 5 is a horizontal cross sectional view on the line 5—5 Fig. 3. Fig. 6 is a view similar to Fig. 1, showing a slightly modified form. Fig. 7 is a side elevation of the modified form. Fig. 8 is a vertical section on the line 8—8 of Fig. 7.

Referring more particularly to the drawings in which similar reference characters designate corresponding parts throughout, 10 designates a conventional form of hull of a vessel to the opposite sides of which the 55 leaves 11 of my brake mechanism are secured. The leaves 11 have their inner

vertical edges hinged upon the vertical pins 12 on the outer faces of the sides of the hull, about midway the length thereof.

When in inoperative position, the leaves 11 engage against the sides of the hull and the outer or free vertical edges thereof are engaged against the shield strips 13, forwardly of the pins 12 and also secured to the sides of the hull. The shield strips 13 and leaves 11 are of substantially the same length and extend from the upper edge of the hull to within a suitable distance of the lower edge of the hull. The leaves and strips are preferably of such length as to extend downwardly to the curved lower portion 11' of the hull. Thus it will be seen that the leaves, pins and strips are positioned only upon the straight portions of the hull sides.

The leaves 11 are formed of any suitable material and have pivoted to their upper outer corners the outer ends of the rack bars 14 which are slidably engaged over the upper edges of the hull and engaged by the pinions 15 upon the vertical shafts 16 within the vessel and suitably connected with the engine. To operate the leaves 11 the pinions 15 are rotated, thus forcing the rack bars 14 outwardly and compelling the leaves 11 to swing upon the pivot pins 12 until at right angles with the sides of the hull, as clearly shown in Figs. 2 and 6.

A cable 17 is secured at one end to the lower outer corner of each leaf 11 and passes around the horizontal pulley 18 secured to the adjacent side of the hull, then around the vertical pulley 19 adjacent the pulley 18 and also secured to the sides of the hull. The cable is then extended upwardly, over the pulley 20 near the upper edge of the hull and above the pulley 19, then through the side of the hull, as shown at 20, after which the cable is secured to the pinion shaft 16 in order that the cable may be unwound when the pinion shaft rotates in a direction to allow outward movement of the leaf to which the cable is attached and drawn inwardly or wound to move the leaf to inoperative position, thus controlling the movement of the leaf and preventing the same from swinging too rapidly upon its pivot pin. If desired the pinion shafts 16 may be connected to a portion of the engine to be operated thereby or may be provided with separate operating means.

The leaves 11 are braced in their outer

positions by means of the brace rods 21 having looped ends 22 and 23, the looped ends 22 being engaged or linked with the eyes 24 upon the sides of the hull 10, a spaced distance rearwardly of the pins 12, while the eyes 23 are slidably engaged over the curved bars 25 upon the outer faces of the leaves 11, said bars 25 extending transversely across the leaves and having their opposite ends secured to the same. It will be seen that when the leaves 11 are in their outer or operative positions, the loops 23 of the rods 21 are at the other ends of the bars 25, thus securely bracing the leaves. When the leaves 11 are in their inoperative positions, however, the loops 23 are near the inner ends of the bars 25. Any number of rods 21, eyes 22 and bars 25 may be provided but I have shown each leaf 11 as braced by three rods 21 and a corresponding number of eyes 22 and bars 25.

Each guide strip 13 is preferably of substantially triangular form in cross section, the vertical edges of the strip being engaged 25 against the face of the hull and the strip being secured along its forward edge or corner to said hull. As the opposite edge of the strip is free, the face thereof adjacent the outer vertical edge of the leaf 11 will bear 30 against said vertical edge and thus prevent casual movement thereof. The guide strips 13 also serve to prevent the water from playing against the forward edge of the leaves 11 and forcing the latter outwardly.

The modified form shown in Figs. 6, 7 and 8 includes the leaves 26 hinged at their inner vertical edges upon the pivot pin 27 on the straight portions of the sides of the hull 28 and adapted to be swung upon said 35 pins by means of the rack bars 29 with which the pinions 30 mesh, said pinions being mounted on the upper ends of the vertical shafts 31, the same as in the preferred form. The cables 32 have their other ends 40 connected with the lower outer corners of the leaves 26 and pass around the vertical pulleys 33 and the spaced horizontal pulleys 34 and 35 and through the openings 36 in the sides of the hull. In this modified form, 45 however, the inner ends of the cables 32 carry the counterbalancing weights 37 to prevent too rapid movement of the leaves 26 upon their pins 27. In this modified form, the long curved bars are dispensed 50 with and the eyes 38 are secured to the leaves 26 near the outer vertical edges thereof with

the forward ends of the brace rods 39 engaged therein while their rear ends are engaged in the eyes 40 upon the sides of the hull adjacent the vertical pins 27, it being 60 understood that the brace rods 39 are suitably bent adjacent their rear ends for engagement around the rear vertical edges of the leaves 26 when the latter are in their closed positions or inoperative positions. 65

When it is desired to employ this mechanism for braking the speed of the vessel, the pinion shafts are rotated in the proper direction to cause the rack bars to move outward and thus free the outer vertical edges 70 of the brake leaves of the guide strips and allow said leaves to move outwardly or swing upon their pivot pins. It will be apparent that as the leaves are braced at their operative positions upon opposite sides of 75 the vessel, they will effectively serve to brake the speed of the vessel. It will also be apparent that it is simply necessary to rotate the pinions in an opposite direction and draw in the cable to return the leaves to 80 their closed or inoperative positions, the guide strips serving to properly guide the free edges of said leaves and retain the same adjacent the sides of the vessel.

It will be apparent that minor changes 85 in the details of construction may be resorted to in the scope of the claim without departing from the spirit of my invention.

What is claimed is:

In a brake mechanism for vessels, the 90 combination of a hull, a leaf pivotally mounted on the side of the hull with its axis of rotation disposed vertically with respect to the hull, means for swinging said leaf to positions against and at an angle to the hull and means for bracing the leaf when the latter is disposed substantially at right angles to the hull, said means comprising an arcuate rod disposed transversely of the leaf and having its terminals secured thereto, a 95 U-shaped bracket secured to the hull and disposed longitudinally of the latter, and a brace rod having its terminals slidably engaged with the arcuate rod and bracket respectively. 100

In testimony whereof, I affix my signature, in presence of two witnesses.

SAM. S. CENTOFANT.
